United States Patent Office

Des. 211,896
Patented Aug. 6, 1968

211,896

CASE FOR A CLOCK OR SIMILAR ARTICLE

Rhys D. Miller, Walnut Creek, Calif., assignor to
Chan Miller Smith, Oakland, Calif., a partnership
of California

Filed Oct. 18, 1967, Ser. No. 9,054

Term of patent 7 years

(Cl. D42—7)

FIG. 1.

FIG. 2.

FIG. 3.

FIG. 4.

FIG. 5.

FIG. 1 is a perspective view of a case for a clock or similar article showing my new design;

FIG. 2 is a top plan view thereof;

FIG. 3 is a front elevational view thereof;

FIG. 4 is a side elevational view thereof; and

FIG. 5 is a bottom plan view thereof.

The broken line showings of a clock face and hands in FIGS. 1 and 3 are for illustrative purposes only.

I claim:

The ornamental design for a case for a clock or similar article, as shown and described.
